UNITED STATES PATENT OFFICE.

MICHAEL H. CONNOR, OF HAVERHILL, MASSACHUSETTS, ASSIGNOR, BY
MESNE ASSIGNMENTS, TO ELIZABETH T. CONNOR, OF SAME PLACE.

LEATHER-STAKING MACHINE.

SPECIFICATION forming part of Letters Patent No. 605,272, dated June 7, 1898.

Application filed September 27, 1897. Serial No. 653,100. (No model.)

To all whom it may concern:

Be it known that I, MICHAEL H. CONNOR, of Haverhill, in the county of Essex and State of Massachusetts, have invented certain new and useful Improvements in Leather-Staking Machines, of which the following is a specification.

This invention relates to leather-staking machines employing two jaws which operate on opposite sides of a hide, skin, or piece of leather in such a manner as to stretch, scrape, and soften the same. The skin is held at one end by an operator, and the jaws are reciprocated in unison and are closed upon the skin, so as to exert a scraping and stretching action thereon during their backward movement away from the operator and opened to release the skin when moving in the opposite direction. The jaws are reciprocated by means of a pitman-rod connected with a revolving fly-wheel mounted on a drive-shaft. The opening and closing operation of the jaws has heretofore been accomplished by means of a cam located on the drive-shaft, the said cam operating upon a rocker-arm which is connected with suitable mechanism for opening and closing the jaws. When the machine is running, the operation of the cam and its connections creates a great deal of noise and vibration, and the mechanism is open to the further objections that it absorbs an undue amount of power and is unnecessarily complicated.

It is the object of my present invention to provide a leather-staking machine which shall be simple in construction and which shall be free from the above-mentioned objectionable qualities of existing machines.

It is also the object of my invention to provide a mechanism for opening and closing the jaws of a leather-staking machine which can be applied to machines of existing pattern with only slight alterations of structure.

With these objects in view the invention consists in the novel features of construction and arrangement which I shall now proceed to describe and claim.

Reference is to be had to the accompanying drawings, forming a part of this application, in which—

Figure 1 represents a side elevation of a leather-staking machine constructed in accordance with my invention. Fig. 2 represents a top plan view thereof.

The same reference characters indicate the same parts in both the figures.

In the drawings, *a* indicates the frame of the machine, and *b* the operating-table, arranged on an incline at one end.

c designates a guideway having an inclination corresponding to that of the operating-table, and *d* designates a slide or carrier mounted to travel in suitable grooves on said guideway. The slide *d* is reciprocated by means of a pitman-rod *e*, connected with a fly-wheel *f*, which is mounted on a drive-shaft *f'*.

g and *g'* designate the two jaws, which operate on the skin, the upper jaw *g'* being securely affixed to the slide *d* and the lower jaw *g* being pivotally connected to the upper jaw at *g'*. A spring *h* connects the rear ends of the two jaws and tends to hold their forward or working ends apart. On the under side of the pitman *e*, near the end which is pivoted to the slide *d*, is affixed a roll *i*, which bears against a contact-plate or chafing-plate *k*, arranged on the upper side of the lower jaw *g*. When the roll *i* presses downwardly on the chafing-plate *k*, the forward end of the lower jaw *g* moves in the direction of the upper jaw *g'*, and when said roll ceases to press downwardly on the chafing-plate the spring *h* causes said lower jaw to move in the opposite direction, so as to separate the two jaws at their forward ends.

The necessary movement of the roll is imparted by the pitman *e* in its transverse travel when the fly-wheel *f* revolves in the direction of the arrow *x*, Fig. 1. The chafing-plate *k* is pivoted at its rear end *k'* to a metal plate or fitting *g''*, to which the lower jaw is secured, and is provided with an adjusting-screw *k''*, which screws through the plate *g''* and bears on the under side of the chafing-plate. Instead of making the contact portion of the chafing-plate *k* flat or of such a shape as to produce an abrupt contact between it and the roll on the pitman I prefer to produce a cam effect at the place of contact by providing the chafing-plate with

100

a projection k^3 , which forms an inclined abutment for the roll to press against, as seen in Fig. 1.

The forward end of the upper jaw g' is provided with a roll j and polishing-blade m , and the lower jaw is provided with a blade o , for removing wrinkles from the skin, and a scraping-blade n . The skin is presented to the action of the jaws by an operator standing at the end of the table b , who grasps the skin by its margin, and also holds it in place between his body and the edge of the table, so as to withstand the drawing action of the jaws.

The devices at the ends of the jaws for acting on the skin form no part of my invention and may be of any approved construction.

By means of my invention I have provided a simple, cheap, light-running, and comparatively noiseless leather-staking machine, and have at the same time furnished a mechanism which can be applied to machines already in use of the general type illustrated in my drawings without making extensive alterations in structure.

By altering machines of the present type to accord with my invention a great saving will be effected in the power required to run each machine, a large number of parts will be dis-

pensed with, and the machines will run with less noise and vibration than formerly.

It is evident that various details of the above-described construction may be altered without departing from the spirit of my invention.

I claim—

In a leather-staking machine having an inclined guideway and an inclined operating-table, the combination with the pivotally-connected working jaws and the slide rigidly secured to the upper jaw, and operating in the guideway, of a pitman-rod pivotally connected with the slide, a roll carried by said pitman-rod, a contact-plate pivotally connected to the lower jaw and having an abutment provided with a concave inclined side against which said roll bears, and means for adjusting said contact-plate to regulate the pressure of the jaws upon the work.

In testimony whereof I have signed my name to this specification, in the presence of two subscribing witnesses, this 21st day of September, A. D. 1897.

MICHAEL H. CONNOR.
